United States Patent Office.

HENRY STANLEY, OF ST. LOUIS, MISSOURI, ASSIGNOR TO G. & W. TODD & CO., OF SAME PLACE.

Letters Patent No. 82,888, dated October 6, 1868.

IMPROVEMENT IN OIL-CUPS.

The Schedule referred to in these Letters Patent and making part of the same.

TO ALL WHOM IT MAY CONCERN:

Be it known that I, HENRY STANLEY, of St. Louis, in the county of St. Louis, and State of Missouri, have made certain new and useful Improvements in Automatic Oil-Cups; and I do hereby declare that the following is a full and clear description thereof, reference being had to the accompanying drawings, and to the letters of reference marked thereon.

This invention relates to an automatic oil-cup for lubricating journals or other machinery-bearings. The peculiarities of the invention consist in combining a wooden necking with a glass or metallic cup, and to sundry other details of construction, hereinafter more fully explained.

The advantages of the wooden necking are, that the parts are more cheaply constructed, and more easily applied to the bearing whereon they are to be used.

To enable those skilled in the art to make and use my improved oil-cup, I will proceed to describe its construction and operation.

Figure 1 of the drawings is a central sectional elevation of the improved cup.

Figure 2 is an elevation of the wooden necking or coupling-piece.

Figure 3 is an elevation of the metallic cap or diaphragm which covers the top end of the necking-piece, and forms the bottom of the oil-chamber.

The cup, A, may be made of metal, but I prefer to make it of glass, with the top part of it reinforced at *a a* for the purpose of forming a substantial seat for the plug *a'* which will be ground into its seat. The necking or coupling-piece, B, will be of wood, and, as is clearly shown in fig. 2, will have a pin or tenon, *b*, on one end for passing up into and securing it to the cup A, and a similar pin or tenon, *b'*, on its other end for attaching it to the bearing-box that is to be lubricated. The great advantage of using this wooden piece B consists in the facility with which it may be attached to the bearing-box by whittling off the pin or tenon *b'* so as to fit it to the lubricating-aperture of the bearing-box. The piece B being of wood, the aperture *b*, through which the oil descends from the cup A to the bearing, will necessarily have to be too large for an economical use of the lubricator; hence I place a metallic cap, C, over the top end of the tube *b*, which cap forms a diaphragm at the bottom of the oil-cup, and between it and the coupling-piece B. Through this diaphragm a small orifice, *c*, is made of just sufficient size to admit the required amount of lubricant to the bearing. In assembling the parts, some cementing-material or wax will have to be interposed between the parts A and B, to prevent a leakage of the lubricator through the joint.

Having described my invention, what I claim, is—

The combination of the oil-cup A, stopper *a'*, wooden end-piece B, slotted at *b*, and capped by the metallic cap C, having the minute perforation *c*, substantially as hereinbefore set forth.

In testimony of which invention, I hereunto set my hand, in presence of—

HENRY STANLEY.
